PNEUMOTHORAX DEVICE

Milton Sills Lloyd, Staten Island, N. Y.

Application April 3, 1940, Serial No. 327,691

6 Claims. (Cl. 128—184)

This invention relates generally to apparatus for the production of suction or pressure, and more particularly to a pneumothorax apparatus especially suitable for the introduction of air pressure into the pleural cavity.

Among the objects of the present invention there is the provision of structure whereby the quantity of air being introduced into the pleural cavity may be accurately measured and whereby the pressure in the pleural cavity may be measured, and may be accurately controlled.

Another object herein lies in the provision of a pneumothorax apparatus which is of a very compact nature so that the same is readily portable in use. In spite of its small size however, the device has a suitable capacity so that even though the device is manually actuated in its pumping action, the number of manual operations to produce a given quantity of air is reduced.

Another object herein lies in the provision of a pneumothorax apparatus in which the various liquid carrying containers may be suitably closed during transportation of the device so that no leakage will occur.

A still further important object of the present invention lies in the provision of certain safety control structure hereinafter more fully described which automatically prevents the introduction into the pleural cavity of any of the liquid which is utilized as a hydraulic pumping medium in the operation of the device.

In accordance with the present invention, the pneumothorax apparatus is of simple and durable construction so that the same may be manufactured at low cost and may thus have a widespread use. The durability of the device permits reliance upon it by the physician since it is fool-proof and will not fail to operate in emergency. Furthermore, even if the attention of the physician is diverted, it is impossible to operate the device in an incorrect manner.

A further feature of the present invention lies in the fact that no auxiliary source of power is required so that the same may be properly operated wherever the patient may be located regardless of the proximity of any electrical power source.

A further feature of the present invention lies in the fact that in accordance with the present construction, the internal portions of the mechanism may be maintained in a sterile condition and the air which is introduced into the pleural cavity is filtered so that foreign matter is automatically removed therefrom.

These objects and other incidental ends and advantages will more fully appear in the progress of this disclosure and be pointed out in the appended claims.

5 In the drawings, similar reference characters designate corresponding parts throughout the several views, in which:

Fig. 1 is a view in perspective showing an embodiment of the present invention as set up and ready for use. In this figure the hydraulic pumping fluid is shown in the upper container and at the beginning of the pumping operation.

Fig. 2 is an enlarged central vertical sectional view of the pumping means.

Fig. 3 is a fragmentary view taken similarly to Figure 2, showing, however, the pump in an inverted position and the valve rotated through 180° as compared with Figure 2.

Fig. 4 is a fragmentary elevational view as might be seen from the right side of Figure 2 and showing in detail the valve means.

Fig. 5 is an enlarged fragmentary vertical sectional view showing in detail the valve control mechanism. In this figure the parts are shown as they would appear if seen from the right side of Figure 3.

Fig. 6 is a view similar to figure 5 with the valve mechanism in an inverted position as compared with Figure 5. In this figure the parts are shown as they would appear if seen from the right side of Figure 2.

In accordance with the invention the pneumothorax apparatus is indicated generally by numeral 10, and includes generally the casing 11, the pumping means 12, the manometer 13, the filter conduit 14, the delivery conduit 15, and the injector 16. The pumping means 12 acts as a source of pneumatic pressure which is delivered to the three-way valve 17. At this point the air under pressure may be injected into the pleural cavity by way of the delivery conduit 15. The manometer 13 permits an accurate check on the various pressures as will be fully described hereinbelow.

45 The pumping means 12 comprises generally a pair of containers 18 and 19 which are preferably of a durable transparent material such as thick glass. In accordance with constructions of the invention which have been found satisfactory in use, each of the containers preferably has a capacity of 330 cubic centimeters. A body element or coupling unit 20 contains the valve means 21 and is adapted for detachable hermetic connection with the containers 18 and 19. The coupling unit 20 has a substantially rectangular

main body portion 22 and along the longest axis thereof is provided with a horizontally disposed conical cylinder 23 in which is disposed a rotatable valve element 24. The portion of the valve element 24 disposed in the conical cylinder 23 is frusto-conical in shape.

The main body portion 22 is provided with a plurality of orifices 25, 26, 27 and 28 which communicate with the conical cylinder 23. The orifices 25 and 27 are aligned on a single vertical axis, and the orifices 26 and 28 are similarly aligned. The body portion 22 is provided with another pair of orifices 29 and 30 which are aligned and communicate with the conical cylinder 23.

The body portion 22 is provided with two circular portions, the edges of which extend beyond said body portion, and form the flanges 31 and 32. The circular flanges 31 and 32 have the edges thereof adapted for threaded engagement with the coupling collars 33 and 34. The flanges 31 and 32 have the inner (that is, facing the containers 18 and 19) surfaces thereof provided with counter bores or circular depressions which are adapted to act as seats for the mouths of containers 18 and 19 and are provided with suitably arranged gaskets which lie between the edges of the said mouths of the said depressions. The coupling collars 33 and 34 have integral inwardly extending annular flanges 35 and 36. The internal diameter of the flanges 35 and 36 is slightly greater than the external mouths of the containers 18 and 19 which are in turn of greater diameter than the neck portions 31 and 38 of the containers 18 and 19.

Annular resilient gaskets 39 and 40 are of a particular cross section clearly seen in Figure 2, so that they complement the adjacent surfaces. In assembling the coupling collars 33 and 34 on the mouths of the containers 18 and 19, the coupling collars are first placed over the mouths of the bottles so that they rest upon the neck portions 31 and 38 respectively. Subsequent to this operation the resilient gaskets 39 and 40 are stretched into place over the mouths of the containers 18 and 19 so that the said gaskets act, not only to promote a hermetic seal thereat, but also act to prevent the coupling collars from falling off the mouths of the containers. If desired, the gaskets 39 and 40 may be bonded to the internal surfaces of the coupling collars 33 and 34.

The orifices 29 and 30 are counterbored to provide seats for the air inlet tubes 41 and 42, which are preferably composed of a non corrodable material such as brass or monel metal. Graduated indicator strips 43 and 44 are affixed to and project laterally from the tubes 41 and 42. The graduation on the strips 43 and 44 may be at any suitable intervals as desired. The tubes 41 and 42 may be either permanently affixed within the orifices 29 and 30 or may be frictionally detachably engageable therewith. The tubes 41 and 42 are of sufficient length when supported as described, so that they reach almost to the bottoms of the insides of the containers 18 and 19.

The rotatable valve element 24 is provided with a plurality of channels or passages 45, 46 and 47. The passage 45 extends through the handle portion 48 of the said valve element and diverges at substantially a right angle to be in line with either orifice 29 or orifice 30 when the valve element 24 is properly seated within the conical cylinder 23. The passage 46 is angularly disposed within the valve element 24, as clearly seen in the drawings, so that one end thereof

5 may line up with the orifice 25 or 21 while the other end will line up with the orifice 26 or 28.

The passage 47 is disposed in the delivery portion 49 of the valve element 24 and is of irregular configuration so that the inner end of passage 47 is adapted for ultimate communication with either orifice 25 or orifice 27. The valve element 24 is maintained in rotatable operative position in conjunction with the conical cylinder 23 by means of the washer, expansive coil spring and nut assembly 10. The delivery portion 49 is adapted to be connected to the filter conduit 14 in any suitable manner, as for example, by the coupler tube 51 which is elastically engaged by the lower end of the conduit 14 and is frictionally engaged within the outer end of the passage 47.

The valve control mechanism generally indicated by numeral 52, includes detents 53 and 54 which may be small horizontally disposed pins 20 which project from the surface 55 of the main body portion 22. The radially projecting pin 56 coacting with the detents 53 and 54 limits the rotation of the valve element 24 to 180° about the horizontal axis. A double pawl 57 includes the 25 ratchet ends 58 and 59. The pawl 57 is loosely pivotally mounted upon block 60, which is in turn attached to the vertical surface 61' of the body portion 22. The configuration of the free end of the pawl 57, is such, and the position thereof with 30 relation to portion 48 is such, that the said portion acts to limit vertical reciprocation of the free end of said pawl. The portion 48 disposed adjacent the pawl 57 is provided with a pair of 35 diametrically opposed outwardly projecting radial pegs 61 and 62 which coact with said pawl. The outer end of the handle portion is provided with a handle 63 having at the periphery thereof a guide pointer 64.

The casing 11 is composed of a pair of box-like elements 65 and 66; the element 65 may be considered as the box bottom and the element 66 as the cover member. The two box elements are hingedly interconnected, provided with a handle 67, latching means 68, and adjustable brace 69. The internal shape and size of the box bottom 65 is such that it is able to contain the pumping means 12 while the inside of the cover member 66 has attached to the inner surface thereof the manometer 13. Since the construction of the manometer and its use in connection with the measuring of pneumatic pressures is well known in the art, the same will not be described in very great detail.

The U tube 70 is maintained in position with 55 relation to the cover member 66 by means of a pair of clips 71. The free end of the manometer is provided with a stop cock 72. The filter element 73 is preferably composed of a cylinder of 60 transparent material and has packed therein any suitable filter elements such as cotton "wool," or glass "wool." The delivery conduit 15 may be composed of any suitable tubing such as rubber, and the injector 16 is preferably a hollow hypodermic type needle associated with the free end 65 of the conduit 15 by means of a connector 74.

Operation

The apparatus is preferably ordinarily shipped 70 in an empty condition to save weight. To prepare the apparatus for use the containers are connected to the coupling unit 20 by means of the coupling collars 33 and 34. The apparatus will now appear as seen in Figures 1 and 2. The control valve handle 63 is rotated to the "working position" (with the indicator guide pointer

64 pointing upwards). By any suitable means such as the ordinary Luer syringe, water is injected through the outflow port, that is, the outer end of the passage 47, the coupler tube 51 having been previously removed. The water, as desired, may contain any suitable coloring matter and/or germicidal agent. The coloring matter serves the purpose of making the liquid more easily visible so that volumetric readings may be readily taken and the antiseptic will act to prevent any bacterial growth occurring in the water. The water is injected through passage 47 and will flow into the container 19. The filling operation is continued until the water level is even with the lower margin of the collar 34. The valve element 24 is now rotated through 90° so as to close all of the orifices 25 to 30, inclusive. The bottles are now reversed so that the bottle 19 is on top. The water level should then reach the top of the graduated scale 44. If it does not, the containers may be again reversed and sufficient water added by the same means to bring the water up to the desired level. The total volume will then be 330 cubic centimeters which, as stated above, is a preferred capacity. The stop cock 12 is removed from the open end of the manometer 10, and preferably with an eye dropper water is placed within the manometer tube until the water level in both arms of the U tube is at zero on the scale 15. Coloring matter may be added to the water in the manometer also. Tincture of metaphen makes a suitable vehicle for this purpose. About two cubic centimeters is sufficient to color the water in the containers, and four drops for the manometer. In both instances the coloring matter should be put in first and the water added. Potassium permanganate and the aniline dyes are unsuitable as they are likely to impart the color to the glass. The containers may, of course, be dismounted by loosening the collars 33 and 34 about the neck of either or both of the containers. Apart from the necessity of replacing a container due to breakage, this is not necessary, since the containers can be either filled or emptied through the outflow end of the air control valve. The valve stem or rotatable element 24 may be freed by removing the nut, spring, and washer assembly 50 from the outflow end thereof, and the ratchet fork or pawl 57 may be removed by removing the screw in block 60.

The manometer 13 is located in the lid or cover member 66 of the carrying case 11. When the lid is raised, the stop cock 12 is opened, (the indicator handle of the stop cock standing in a vertical position). The three-way valve 17 is turned so that the indicator points to the right, as seen in Figure 1, and ordinarily no change will then be required in the manometer at any time, that is to say, initial treatment refill or deflation. The pumping means 12 is placed in an upright position in the box with the particular container within which the water is then located placed uppermost. The passage 47 is connected by means of the conduit 14 to the lower end of the valve 17.

With the guide pointer 64 pointing in a horizontal direction, the needle injector 16 is inserted into the chest in the usual way. When a manometer reading has been obtained, the handle 63 is turned to its working position with the guide pointer 64 pointing upward. Air immediately begins to flow into the chest. Air enters the container 18 from which the liquid is flowing, by traveling through the passage 45, the orifice 29, 75

and the air inlet tube 41. When the container 18 has emptied, the position of the container is reversed, the valve means 21, being operated as described hereinbelow. In the now inverted position, the container 19 will be uppermost and air will enter the container 19 from which the liquid will then be flowing, by going through the passage 45, orifice 30, and tube 42. With the apparatus components of the size as indicated in Figure 1, the transfer of the liquid from the upper bottle to the lower bottle will be completed in about one minute when the external pressure is equal on both sides. A reading is made from the upper scale as the fluid descends. A centimeter scale may be used on the indicator strips 43 and 44 so that each centimeter of fall will indicate a delivery to the chest of approximately 35 cubic centimeters of air, down to 8 centimeters (280 cubic centimeters). The narrowing of the neck of the bottle reduces the volume of the remaining liquid to approximately 50 cubic centimeters. A manometer reading is generally taken after each 100 cubic centimeters of air is delivered. The manometer reading may be obtained by simply turning the handle 63 to a position in which the guide pointer is sufficiently off vertical to close the passage through the valve stem.

If, for any reason, a greater air pressure is desired, the speed of delivery of air to the chest may be increased by attaching a rubber bulb with a Luer connection to the inflow end of the valve and forcing air into the upper bottle under pressure. When the uppermost container is emptied, the valve is closed and the pumping means 12 is inverted. In turning the pumping means, a useful precaution is to keep the indicator 64 pointed upwardly. The return of the valve to the working position is then compensatory and kinking of the conduit is prevented. The upper container should always be completely emptied before the apparatus is inverted.

For deflation the apparatus is used in the same way except that the coupler tube 51 is placed into the outer end of the passage 45.

When the apparatus is not used, a positive or negative pressure (above or below atmospheric pressure) is maintained equal to the height of a column of liquid in the system. This begins at 60 about 14 centimeters and falls as the liquid descends until it equals about 2 centimeters when the upper container is emptied. The length of the graduated scales are approximately 12 centimeters and the depth of the valve is approximately 2 centimeters.

If the injector 16 which is used has a large enough internal bore to carry the full flow of air without back pressure, intrapleural readings may be taken at any time, without arresting the delivery of air, by subtracting the existing pressure in the system from the contemporaneous manometer reading. Hence, with the water level in the upper container at a "5," a pressure of plus 9 centimeters will be delivered. If the manometer reading is then plus 8, plus 2, the intrapleural pressure will be minus 1, minus 7. When the instrument is in use, the manometer reading represents the sum of the intrapleural pressure plus the pressure delivered by the instrument. It is, therefore, obvious that, when the known pressure delivered by the pneumothorax instrument is subtracted from the manometer reading, the result will represent the intrapleural pressure. In extreme changes of temperature, it is advisable before using to hold the system with the empty bot-

tle upward and turn the valve to the working position. This permits balancing the atmospheric pressure.

Transportation of the complete apparatus with all valves closed will result in no loss of the liquid from the system.

The operation of the valve control mechanism will be best understood by a perusal of Figures 4, 5 and 6 of the accompanying drawings. As viewed in Figure 2, it will be seen that all of the 10 radially arranged portions of the passages 45, 46, 47 are in the same plane. The pin 56, as viewed in Figure 2, projects upwardly and rests against detent 53. The pegs 61 and 62 project horizontally from the portion 48. The position 15 of the parts at this stage is best seen in Figure 6, only the radially disposed portion of the passage 47 being shown in dotted lines for the purpose of clarity. In this position air compressed in the lower container 19 passes outwardly through the 20 passage 41. As soon as all of the liquid has flowed from the container 18 into the container 19, the handle 63 is grasped and is rotated through 90° in a counter-clockwise direction, as viewed in Figure 6 (the detent 53 preventing rotation at this time in clockwise direction). The parts will then take the position shown in Figure 4 in which the peg 61 is prevented from rotating in a counter-clockwise direction by the action of the ratchet end 58. At this stage the pumping means 12 is inverted and the action of gravity will cause the pawl 57 to drop and the parts 25 will take a position in which the ratchet end 59 rests upon the upper surface of the portion 48. In this position it will then be impossible to rotate the handle 63 in a clockwise direction, since the peg 62 will abut the ratchet end 59. The handle 63 is next rotated in a counter-clockwise direction, as viewed in Figure 5, until it reaches the position shown in said figure. When 30 the pin 56 strikes the detent 54, this sequence of operations is continued until the desired pressure or vacuum is created by the pumping means. It, therefore, follows that at any given position of the pumping means, that is, whether or not the container 18 or the container 19 is lowermost, only two positions of the valve stem or rotatable element 24 are possible, one, a working position in which the passage 47 is disposed downwardly, and two, an off position in which the inner end 35 of the passage 47 and the corresponding orifices 25 or 27 are disaligned.

It may, therefore, be seen that I have disclosed a novel and useful pneumothorax device which is compact, light in weight, durable, efficient, very convenient to use and completely foolproof in operation. The device may be composed of durable and yet low-cost materials such as bronze and glass, so that no undesirable corrosion takes place, and the instrument may be sold at low cost and have a long useful life.

I wish to be understood that I do not desire to be limited to the exact details of construction shown and described for obvious modifications will occur to a person skilled in the art.

I claim:

1. A pneumothorax device comprising: a body element, a pair of containers detachably associated with said body element, a plurality of apertures in said body element communicating with each of said containers, and valve means adapted in a first position thereof to permit air under pressure to flow from one container, in a second position to stop air flow, and in a third position to permit air under pressure to flow from the 70

other container, and movable control means restricting the movement of said valve means to permit the flow of air from a container only when it is in the lower position thereof.

2. A pneumothorax device comprising: a body element, a pair of containers detachably associated with said body element, a plurality of apertures in said body element communicating with each of said containers, and valve means adapted in a first position thereof to permit air under pressure to flow from one container, in a second position to stop air flow, and in a third position to permit air under pressure to flow from the other container, and gravity operated movable control means restricting the movement of said valve means to permit the flow of air from a container only when it is in the lower position thereof.

3. A pneumothorax device comprising: a body element, a pair of containers coaxially aligned and detachably associated with said body element which is disposed between said containers, a plurality of apertures in said body element communicating with each of said containers, and valve means adapted in a first position thereof to permit air under pressure to flow from one container, in a second position to stop air flow, and in a third position to permit air under pressure to flow from the other container, and movable control means restricting the movement of said valve means to permit the flow of air from a container only when it is in the lower position thereof.

4. A pneumothorax device comprising: a body element; first and second containers detachably connected to said body element; said body element having a plurality of apertures therein communicating with each of said containers; valve means adapted in the first position thereof to permit air under pressure to flow from the first container, in the second position to stop air flow and in the third position to permit air under pressure to flow from the second container; and gravity operated movable control means preventing manual movement of said valve means to the first position thereof when the device is resting on the second container, and preventing manual movement of the valve means to the third position thereof when the device is resting on the first container.

5. A pneumothorax device comprising: first and second containers each having a neck portion; a coupling unit including a body element, valve means, and gravity operated movable control means coacting with said valve means; said body element detachably engaging both of said neck portions on opposite sides of said body element whereby the containers are oppositely disposed with the body element therebetween, both containers being thereby integrated and movable as a unit; said body element having a plurality of apertures therein communicating with each of the containers, said valve means being adapted in a first position thereof to permit air under pressure to flow from the first container, in the second position to stop air flow and in a third position to permit air under pressure to flow from the second container; said gravity operated movable control means acting to prevent manual movement of the valve means to the first position thereof when the device is resting on the second container, and to prevent manual movement of the valve means to the third position thereof when the device is resting upon the first container.

6. For use with a pneumothorax device of the class having a pair of oppositely disposed containers holding a charge of liquid and which compresses air in the lowermost of the containers when the device is inverted; a valving structure adapted to be connected to each of said containers, said valving structure comprising a body element having a cylinder substantially horizontally disposed when the device is in an operative position, said body element having a plurality of 10 juxtaposed orifices communicating with said containers and said cylinder; a rotatable valve

5 element disposed within said cylinder; means to prevent rotation of the valving element in excess of substantially one hundred eighty degrees; a gravity acting double pawl movably mounted on said body element; a pair of oppositely disposed projections on said valving element coacting with the ends of said double pawl whereby rotation of the valving element is restricted to substantially ninety degrees within the said one hundred eighty degrees.

MILTON SILLS LLOYD.
